ROCKER SUPPORT DEVICE AND THE LIKE

Howard McClellan, Chicago, Ill.

Application May 9, 1956, Serial No. 583,707

7 Claims. (Cl. 155—56)

The instant invention relates to rocker devices. More particularly, it relates to body supports, such as seats and the like, that are supported for a rocking action. Specifically, the invention relates to a spring-type, rockable body support, such as a chair and the like, which is suspended and supported for rocking in a vertical and horizontal plane.

Although reference herein is had to a chair particularly adapted for use by young children, it will be appreciated that the features of the invention are not limited to use in children's chairs.

It has been observed that available rocker devices having or relying on spring means to effectuate the desired movement of the body support comprise a combination of parts, including a spring which is adapted to provide movement in a particular plane so that principally the rocking movement is in either a vertical or in a horizontal plane. Accordingly, in order to effectuate the maximum "ride" with a minimum of energy output on the part of the user, a substantial degree of muscular co-ordination is required. Consequently, exceedingly small children and other persons who do not have the developed muscular control cannot easily obtain maximum ride effect without expending substantial wasted energy.

It is desirable, therefore, to provide a rocking seat or rocking body support which will translate into maximum rocking movement energy that is haphazardly applied against the seat, for example: by the uncontrolled kicking feet of an infant.

It is an object of the instant invention to provide a device of the described class in which a force applied against the seat will result in maximum rocking movement regardless of the direction of the force vector.

Another object of the invention is the provision of a rocking support comprising a combination of parts which are well balanced in order to preclude tipping of the device.

A still further object of the invention is the provision of an adjustable foot-rest kick-plate adapted to vary the distance between the body support member and the kick-plate.

An additional object of the invention is the provision of a rocking chair and the like comprising a seat member suspended between a pair of pivoted arms and on a pair of coil springs, each of which is secured to a base, whereby movement of the body support member may be achieved simultaneously in a vertical and horizontal plane.

Other and further objects of the invention will become apparent from the following description and appended claims, reference being had to the accompanying drawings and numerals of reference thereon.

On the drawings:

Fig. 1 is a side elevation of one embodiment of the instant invention, parts being broken away for the purpose of illustration.

Fig. 2 is a top plan of the device illustrated in Fig. 1.

Fig. 3 is an enlarged detail view of a fragment of the

frame of the side of the seat in elevation and illustrating the mechanism by which the tray is removed.

Fig. 4 is an enlarged fragmentary view looking at the top of Fig. 3.

5 Referring now more particularly to the drawings, an open-ended U-shaped frame 10 provides the base of the device. As illustrated in Figs. 1 and 2, downwardly bent legs 11, shown integral with frame 10, provide the rear stand or support of the device. The frame 10 is of tubular 10 construction. However, it will be apparent that such tubular construction is not critical insofar as the invention is concerned.

The front stand or support is provided by a pair of opposed horizontally aligned bracket members 12 on the 15 lower portion 14 of each of which a wheel 13 is rotatably mounted, as illustrated in Figs. 1 and 2. An elongated and enlarged medially disposed boot abutment forms or comprises the foot-rest or kick-plate 15. The kick-plate 15 is suitably rigidly secured at the opposite ends thereof 20 to opposed bracket extensions 16, only one of which is illustrated in the drawings, in Fig. 1, by suitable fastening means, not shown, whereby said brackets 12 are tied.

As illustrated in Fig. 1, each of the brackets 12 includes an arcuately shaped forward supporting arm 17 having a 25 plurality of preferably equally-spaced apertures 18. Each bracket 12 also includes an upwardly and angularly extending rear arm 19 which is pivotally connected to its respective frame side element or leg 20 by means of a pivot pin 21.

30 By means of a suitable fastener 22 such as a wing bolt and nut, each arcuately shaped arm 17 is releasably secured to its respective frame side element or leg 20. Thereby, adjustment of the kick-plate 15 is achieved by 35 releasing the fasteners 22 and moving the tied brackets 12 to the desired position and resecuring the fasteners 22. The foregoing accommodation permits appropriate spacing of the kick-plate 15 from the body support member 23 so that the device may be employed by persons of varying leg lengths.

40 The body support 23 in the embodiment illustrated herein is a seat or chair-like element which is suspended for a rocking motion or oscillation above the frame 10. The support member 23, herein illustrated, comprises a back rest 24 and a bottom rest 25. The said body support 23 has a pair of rigid side frames or members 26, each of which is shown as being of tubular construction and which are mounted in opposed positions on opposite sides of the support 23, as illustrated in Figs. 1 and 2. The lower end 27 of each side member is suitably secured 45 to the bottom rest 25 by means of a suitable fastener 28. A pair of opposed brackets, generally designated by the numeral 30, are rigidly secured on opposite sides of the back rest 24 by suitable fasteners about midway between the ends of said back rest 24, as illustrated in Figs. 1 and 2. Each of the brackets 30 comprises an encircling 55 or enclosing portion 31 and a flat portion 32. The upper end extensions 29 of said side members 26 extend through the encircling portions 31, respectively, as illustrated in Figs. 1 and 2 of the drawings, whereby said extensions 29 are supported and operably connected to the back rest 24.

60 A transversely extending tie 34 has opposed portions thereof secured to aligned medial portions of opposed frame legs 20 by means of securing elements 33 as illustrated in Fig. 2. The tie 34 has a pair of opposed rearwardly extending, inwardly offset ends 35 that are disposed inwardly of the legs 20. The ends 35 each provide a lower anchor for one of a pair of opposed springs 36 the lower ends of which are snugly mounted about said ends 35, respectively. The opposite and upper ends of said springs 36 are snugly mounted about the upper end extensions 29 of the frame members 26, respectively.

As clearly illustrated in Fig. 2, the anchor elements 35 are disposed outwardly or laterally of the extensions 29 respectively so that when the springs 36 are mounted, as illustrated in the drawings, they are disposed angularly, diverging inwardly from the bottom thereof.

Each of these springs 36 is preferably a coil spring, and it is suggested that the same be of the compression type. Such construction will preclude squeaking of the springs during use of the device as would be encountered if extension-type springs are employed. Additionally, it is related that the springs 36 each have a U-shaped configuration being bent from a straight coil form. Thereby, a weight resistant effect is brought to bear on the body support 23. Also, it will be seen that the closed curved portions 45 of the springs 36 extend rearwardly of the body support 23 and that the springs 36 support the body support 23 at a point rearward of its normal center of gravity.

A pair of opposed, rigid, pivoted, angularly-disposed rods or arms 37 support the body support 23 at opposite sides thereof forward of its normal center of gravity. The rods 37 each are pivoted to a respective side frame member 26 by means of a pivot pin 38; and each of said rods is pivotally secured to a respective leg 20 for rocking movement by means of a pivot pin 39. As illustrated in the drawings, the lower ends of arms 37 are positioned forward of the upper ends thereof when the device is not in use; and said rods converge inwardly from base 20.

Because of the foregoing construction, the body support 23 is supported from forward of its normal center of gravity by the rigid rods or arms 37. The upper end portion of each of the springs 36 will be forced toward the opposite end portion thereof under the normal weight of the user.

It is apparent from the foregoing that when used in its obvious manner a rocking motion will be imparted in the body support which will comprise a plurality of motion components, including motion in a vertical plane and motion in a horizontal plane, or a combination of the two. As the body support moves back and forth, when the device is in use, an oscillating or wave of motion will be set up in the springs 36 and the body support 23 will rock back and forth about an axis defined by the parallel pivots 39. Pivoting action of body support 23 about an axis defined by pins 38 will also be experienced.

Although it is not my intention to be limited to the specific design of the body support insofar as non-essential details are concerned, in the embodiment shown, the device is adapted for use by young children. Accordingly, a tray 40 is mounted on the side members 26. To achieve the mounting of the tray 40, an opposed pair of arms 41, each having a compression-type spring component 42 at its outer end, are secured at the outer ends thereof to said tray 40. To mount tray 40, the inner spring end 42 of each of said arms 41 is inserted through a slot 43 of its respective side support 26, as illustrated in Figs. 3 and 4, the springs 42 securing the arms 41 in the side members 26, respectively. To release the tray 40 from its retained position, springs 42 are manually compressed by engaging the springs 42 with the hands through apertures 44 in the opposite side members. Of course, the springs are thereby compressed permitting the tray to be withdrawn.

While the particular embodiment illustrated in the drawings is for an amusement chair for children, it is evident that with slight modification within the scope of the invention a rocking horse or other animal could be provided; and that the principles attendant in the instant disclosure are readily adaptable for incorporation in chairs for use by adults.

Inasmuch as many changes can be made in the foregoing construction, and inasmuch as many variations

therein could be proposed without departing from the spirit and scope of this invention, it is intended that all matter contained herein shall be considered as illustrative only and not in a limiting sense.

I claim:

1. A rocking support and the like, comprising a frame, a rigid rockable means pivoted to said frame; a body support pivotally connected to said rigid rockable means; a rearwardly curved coil spring under continuous tension secured to said frame and said body support and supporting said body support in positions opposed to said rockable means, coils of said spring being successively compressible longitudinally of said frame.
2. A rocking support and the like, comprising a pair of opposed coil springs under tension, said springs being disposed in inwardly tapering angulation; a body support connected from one end portion thereof to said springs; a pair of opposed pivotable members operably connected from the other end portion of said body support to said body support and adapted to permit pivoting thereof, and a base below said body support, said springs operably connected to said base, said pivotable members pivoted to said base and anchoring said body support whereby tension is maintained on said springs.
3. In a rocking support and the like, the combination with a rockable seat and a frame on which said seat is rockably supported by a pair of compression coil springs bent under tension, the opposite ends of said springs connected to said frame and said seat, said springs being disposed in upwardly and rearwardly diverging planes, and seat anchoring means pivotally secured to each said seat and frame and holding said springs under tension.
4. A rocking support and the like, substantially as defined in claim 3 wherein said seat anchoring means comprise a pair of opposed rigid arms pivotally connected to said seat and pivotally connected to said frame at opposite sides of each thereof.
5. A rocking support and the like, substantially as defined in claim 4 wherein said rigid arms diverge inwardly from the bottoms thereof and normally extend backwardly from the bottoms thereof when the support is not in use.
6. A rocker and the like, comprising a frame; a pair of opposed brackets adjustably and pivotally secured on said frame and having arcuately extending arms, said arms having a plurality of apertures; fastening means releasably securing said arcuately extending arms to said frame; a kick-plate secured to said brackets; a rocking seat member operably connected to and supported by said frame; rocker arm means at opposite ends thereof pivoted to each said frame and seat member, and tension bent compression springs connected to said seat member and said frame in positions opposed from said rocker arm means.
7. A rocking seat and the like, comprising a body support member; spring means under continuous downward tension and including longitudinally bent coils supportingly connected to the back end portion of said body support member and supporting said body support member from behind; rocker arm means pivotally connected to the front end portion of said body support member and anchoring said body support member against the action of said spring, and a frame, said spring means and rocker arm means connected to said frame with said coils successively compressible longitudinally of said frame.
